TO THE AMERICAN WELL WORKS, OF AURORA, ILLINOIS, A CORPORATION OF
ILLINOIS.

PUMPING MACHINERY.

1,169,772.

Specification of Letters Patent.

Patented Feb. 1, 1916.

Application filed May 16, 1910. Serial No. 561,587.

To all whom it may concern:

Be it known that we, MATTHEW T. CHAPMAN and MARK C. CHAPMAN, citizens of the United States, residing at Aurora, in the county of Kane and State of Illinois, have invented certain new and useful Improvements in Pumping Machinery, of which the following is a specification, reference being had to the accompanying drawings.

10 Our invention relates to pumping machinery such as is employed in pumping water from deep wells, and has for its object to provide certain improvements in the construction and operation of such apparatus.

15 One of the objects of our invention is to overcome the side draft incident to the use of a crank acting directly upon the pump-rod as has heretofore been the general practice in deep well pumping machinery.

20 Another object is to provide pumping mechanism of such construction that a longer stroke is secured.

25 A still further object is to provide means for balancing the weight of the pump-rod or rods as well as the weight of the water, thereby equalizing the load so that the action of the pump may be made more nearly uniform.

30 We accomplish these objects as illustrated in the drawings and as hereinafter described.

That which we regard as new is set forth in the claims.

35 In the accompanying drawings, Figure 1 is a side elevation of our improved pump-rod operating mechanism; Fig. 2 is a plan view thereof; Fig. 3 is a vertical cross-section on line 3—3 of Fig. 2; and Fig. 4 is an elevation of the parts shown in Fig. 3 partly broken away.

40 Referring to the drawings, 12 indicates the bed-plate of the pumping mechanism, which rests on a suitable foundation 13 placed over the well. 14 indicates a piston-rod which forms the upper end of the pump-rod and is secured to the uppermost pump-rod section 15, as shown in Fig. 1. Said piston-rod works through a suitable bearing 16 carried by the bed-plate and is secured 45 at its upper end to a cross-head 17, the ends of which are fitted to suitable bearings to receive upright guide-rods 18 19 which rise from the bed-plate and are secured together at their upper ends by a cross-bar 20, 50 as best shown in Fig. 1. The cross-head 17

is provided with a recess at the center to receive the upper end of the piston-rod 14, said rod being secured in place by a detachable plate 21 secured by bolts 22. Thus the pump-rod may readily be disconnected 60 from the cross-head 17 when desired. The ends of the cross-head 17 are projected laterally so that the bearings of the rods 18 19 lie in a vertical plane which is at one side of the piston-rod 14. 65

23 24 indicate gears which are mounted on parallel shafts 25 26, respectively, supported by a suitable frame 27, said gears being arranged to intermesh so that they operate in unison. Said gears are mounted in 70 a vertical plane at the opposite side of the piston-rod 14 from the guide-rods 18 19, as shown in Fig. 1, and are provided, respectively, with crank-pins 28 29, to which the lower ends of pitmen 30 31 are connected. 75 The upper ends of said pitmen are connected with the ends of the cross-head 17 by pins 32, 33, respectively. By arranging the guide-rods 18 19 in a plane which is at the opposite side of the piston-rod 14 from the 80 plane of the gears 23 24 it will be seen that said guide-rods do not interfere with the rotation of the gears and the actuation of the pitmen 30 31.

34 35 indicate pinions which mesh with 85 each other and with the gears 23 24, respectively, as shown in Fig. 1, said pinions being mounted on shafts 36 37, respectively, which are suitably supported by the frame 27, as shown in Fig. 2. One of said shafts, 90 as 36, is the drive-shaft and is provided with fast and loose pulleys 38 39, or other suitable means, such as a directly-connected motor, for driving the same. By this construction power is applied directly to each 95

of the gears 23 24, and, besides, said gears are geared together so that they operate properly in unison, rotating in opposite directions. By this construction we avoid side strain, since the gears 23 24, being of equal diameter and having an equal number of teeth, revolve together at the same rate of speed and carry the crank-pins 28 29 to and from each other equally. Side strain on one will balance or equal side strain on the other, whether in lifting up or forcing down the pump-rod. By connecting the driving pinion 34 with the gear 23 and also with the gear 24 through the pinion 35 which meshes with the pinion 34 at the side opposite the 100 105 110

gear 23, the pressure upon said driving pinion is equalized.

The pumping apparatus described is intended primarily for use in connection with 5 a double-acting pump, such as those shown and described in the application for patent of Robert E. L. Holmes, Serial No. 337,321, filed October 3, 1906, and the application for 10 patent of Matthew T. Chapman, Serial No. 426,556, filed April 11, 1908, although it may be used with other forms of pumping mechanism.

For the purpose of balancing the weight 15 of the pump-rod or rods, we provide each of the shafts 25 26 with a counterbalancing weight 40 41, which, as best shown in Figs. 3 and 4, is in the form of a segmental casing having pockets 42 which may be filled with cement or other suitable material so that 20 such weights properly counterbalance the weight of the pump rods in the well. Said counterbalance segments are fixedly secured to and keyed upon their respective shafts in any suitable way so that they rotate with 25 said shafts. They are placed at the opposite sides of their respective shafts from the crank pins 28 29, respectively, as best shown in Fig. 1. By this construction by properly regulating the amount of material placed in 30 the pockets 42 the counterbalancing weights may be made to accurately balance the pump rods so that the power applied for pumping will be uniform for raising the water on both the up and down strokes in double-acting 35 pumps, or for the lifting stroke alone in single-acting pumps. When used in connection with a single-acting pump, sufficient weight should be added to counterbalance the weight of the rods and also the weight of 40 the water to be lifted.

43 44 45 46 indicate braces secured to the upper ends of the guide-rods 18 19 for properly bracing them and holding them rigidly in position.

45 47 48 indicate drums mounted on the ends of the shafts 25 26 for use in hoisting the pump rods and plungers out of the well, when the plunger in the well has become worn and repairs are necessary. In using 50 said drums the piston-rod 14 is suitably secured so that it cannot drop into the well and the cross-head 17 and pitmen 30 31 are removed. If desired also the counterbalance weights 40 41 may be disconnected from 55 their respective shafts. Hoisting tackle con-

sisting of ropes and pulleys is then hung centrally over the well, the loose end of the rope being wound around one of the drums and the hoisting tackle connected to the piston-rod. By then operating the gears 23 24 60 the pump rods and plunger may be withdrawn from or lowered into the well.

The construction shown in Fig. 1, in which the gears 23 24 intermesh, is the best embodiment of our invention, but our invention is 65 not limited to a construction in which such gears intermesh since satisfactory results may be secured by driving the gears through the pinions 34 35. The claim hereinafter made should therefore be construed accordingly.

By constructing the operating mechanism as described, we avoid side draft and are able to secure a longer stroke for the pump. We also balance the operating mechanism so that 75 the action of the pump is made uniform and smooth, and it is therefore much more efficient than constructions heretofore in use.

Our improved construction of pump may be used for pumping oil from oil wells or 80 for pumping any other liquid. We wish it to be understood that our invention is not limited to the specific construction shown and described, except in so far as such construction is specifically claimed, but includes 85 the use of mechanical equivalents, and the claims are to be construed accordingly.

That which we claim as our invention, and desire to secure by Letters Patent, is,

In a pumping mechanism, the combination 90 of a standard, two shafts journaled therein a short distance apart, intermeshing gears mounted on said shafts, pitmen connected with the front faces of said gears, a cross-head pivotally connected with said pitmen, a pump rod connected with said cross-head midway between the connections of said pitmen thereto, guide rods upon which said cross-head is vertically slidable located slightly in advance of said pitmen, and segmental casings mounted on said shafts respectively adapted to be filled more or less for counterbalancing the weight of the 95 pump rod.
